DESIGN FOR A RECEPTACLE FOR TOOTH- BRUSHES AND THE LIKE

Alton T. Winner, Oaklyn, N. J.

Application February 18, 1943, Serial No. 109,566

Term of patent 7 years

To all whom it may concern:

Be it known that I, Alton T. Winner, a citizen of the United States, residing at Oaklyn, in the county of Camden and State of New Jersey, have invented a new, original, and ornamental Design for a Receptacle for Toothbrushes and the like, of which the following is a specification, reference being had to the accompanying drawing, forming part thereof.

I claim:

The ornamental design for a receptacle for toothbrushes and the like, as shown.

ALTON T. WINNER.
